United States Patent

Des. 235,480
Patented June 17, 1975

235,480

PORTABLE TYPEWRITER

Karl T. Baughman, Lake Forest, Ill., assignor to Sears,
Roebuck and Co., Chicago, Ill.

Filed Mar. 12, 1973, Ser. No. 340,328

Term of patent 14 years

Int. Cl. D18—01

U.S. Cl. D64—11 A

Fig. 3

FIG. 1 is a front, top and left side perspective view of a portable typewriter showing my new design with the case in closed position;

FIG. 2 is a left side elevational view;

FIG. 3 is a view similar to FIG. 1 with the case in open position;

FIG. 4 is a top and right side perspective view of the typewriter with the case removed;

FIG. 5 is a front elevational view thereof;

FIG. 6 is a rear elevational view thereof; and

FIG. 7 is a rear elevational view with the case in closed position.

I claim:

The ornamental design for a portable typewriter, as shown and described.
